UNITED STATES PATENT OFFICE.

HARRY S. FOLGER, OF CHICAGO, ILLINOIS.

TYPE-HOLDER.

SPECIFICATION forming part of Letters Patent No. 748,715, dated January 5, 1904.

Application filed November 3, 1902. Serial No. 129,876. (No model.)

To all whom it may concern:

Be it known that I, HARRY S. FOLGER, a citizen of the United States of America, and a resident of Chicago, county of Cook, and State 5 of Illinois, have invented certain new and useful improvements in Type-Holders, of which the following is a specification.

My invention relates to type-holders, and has for its object the construction of an object 10 long holder so arranged that type may be held in lines running either longitudinally or transversely and also so arranged that the line-dividing plates of such holder will be held from displacement and yet be adjustable, so as to accommodate type of different sizes. There are added screws by which the type are 15 clamped and held. When so made, the holder becomes what I term a "reversible" holder. For example, if the holder be of a size suitable 20 for printing on a postal card it may be filled with a large number of short lines or a less number of longer lines, and in each case the type will be securely held in place by a moderate pressure.

Another object of my invention is to provide such a holder with a spring clamping device on its back, by which it may be held in a press adapted for the purpose, and also to provide it with a removable handle by means 30 of which it may be used as a hand-stamp instead of a press-stamp. This interchangeable character of holders of this kind is desirable, because they are usually of a size which may be used by hand, but are best 35 adapted for use on a press. The question as to whether the holder be used as a press-stamp or as a hand-stamp will often turn upon the manner in which the type are distributed in the type-holding portion, and this last will 40 sometimes depend upon whether the lines run transversely or longitudinally.

In the accompanying drawings, Figure 1 is a face view of the holder, the lines of type running transversely. Fig. 2 is a similar view 45 with the lines running longitudinally. Fig. 3 is a section of Fig. 1, the type and the line-dividing plates being omitted. Fig. 4 is an end elevation of Fig. 2. Fig. 5 shows the rear face of the holder, and Fig. 6 is a perspective view of the box portion detached.

In the said drawings, A is a rectangular frame or box provided with bolt-holes A' in

its sides and ends adjacent to the corners and with screw-holes A² in one side and in one end. Through corresponding holes A' in opposite ends or in opposite sides are run the bolts B, which are secured in place by the nuts B'. On these bolts are strung the plates C, which are held and guided in the box by said bolts, but which are free to slide lengthwise thereon. These plates are comparatively thin and have a width about equal to the depth of the box. Between these plates are inserted the type T, and the clamping-screws S in the holes A² serve to press the type and line-dividing plates firmly together, so as to hold the type securely in position. When the bolts B run longitudinally through the box A, the lines of type and the line-dividing plates C run transversely, as shown 70 in Fig. 1. In this case the bolts are long and the plates are short. When the bolts run transversely, the lines and the plates run longitudinally, in which case the bolts are short and the plates are long, as shown 75 in Fig. 2. Both long and short bolts and plates are furnished with a box, and when it is desirable to change the arrangement shown in Fig. 1 to that shown in Fig. 2 all that is necessary is to remove the nuts B' 80 on one end of the bolts B and withdraw them. This leaves the plates C free to be removed. The long plates and short bolts are then substituted, and the screws S are removed from the end to one side, when the 85 arrangement is as shown in Fig. 2. For the purpose of permitting the use of small type more plates C are strung on the bolts B than are ordinarily necessary. These extra plates are simply bunched together at the end or side 90 of the box, as shown in the drawings. As thus made the plates C provide type-holding channels, the bolts B and the screws S provide means by which these channels are individually adjustable in width, and the box-like 95 form of the holder and the holes A' arranged so as to register in its opposite ends and its opposite sides provide means by which the lengths of these type-holding channels may be changed by reversing their direction in the 100 holder.

The frame or box A may be made in any desired manner out of material of any desired thickness. Preferably it is made of

thin sheet metal. In the drawings it is shown as if pressed or molded with the sides and ends united at the corners. It may be and generally is, however, made from sheets which have their ends and sides bent upward without being united at the corners. It is quite practicable to do this, as the sides or ends having the clamping-screws S are supported by the bolts B, and the sides or ends not so supported are not subjected to any strain whatever.

On the back of the frame or box A are secured the spring-strips D, one end of each of which is formed into a hook D' and the outer end of each of which terminates in a spring-catch D². These hooks and catches are made to engage suitable projections on a press and furnish means by which the holder may be quickly connected to and disconnected from such press.

On the center of the back of the box is a washer E, secured in place by brazing or otherwise. This washer forms a thin boss which is tapped out, and into it is screwed the removable handle E'. The handle is made removable, because the holder cannot be attached to a press while the said handle is in place; but the strips D are not necessarily removable, because they do not interfere with the use of a holder as a hand-stamp.

What I claim is—

1. In a type-holder, a frame in the form of an oblong box having holes in its opposite ends and sides near its corners whereby bolts may pass through said frame in either of two directions, bolts extending through said frame in one of these directions, and line-dividing plates supported by and adjustable on said bolts. 35

2. A reversible type-holder consisting of a box-shaped frame, line-dividing plates therefor, bolts upon which said line-dividing plates are held and guided, screws for clamping type and said plates together in a direction parallel to the axes of said bolts, and means whereby said bolts may be made to pass through said frame in either of two directions whereby lines of type are held either longitudinally or transversely in said holder. 45

3. In a type-holder, an oblong box formed of sheet metal and provided with registering holes in its ends and sides, parallel rods supported in one set of registering holes and shiftable to the other set, and line-dividing plates supported by and guided on said rods. 50

Signed at Chicago, Illinois, this 30th day of October, 1902.

HARRY S. FOLGER.
